Assignors to
Parlor Stove of same place
Letters Patent No 1365 Issued Dec 18 1860

The schedule referred to in these Letters Patent is making part of the same.

To all whom it may concern;

Bethel Vodder, and Mr. N. S. Vodder, of the City
of Troy, in the County of Rensselaer, and State of New York, and William
D. Sanderson, of the same place, have jointly invented or produced a new and
original ornamental design for Parlor Stove Plates, and we do hereby declare
that the following is a full and exact description of the same, reference being had

to the annexed photographic drawing, which forms a part of this specification.

Our ornamental design for parlor stove plates consists of pillars a, a, and o, o, in a bays or recesses b, b, ornamented with d, pointed caps e, fenced vestibule f, and recessed panels g, g, on the lower portion of the plate, and the pillars h, h, arched and ornamented on a balcony i, recessed panels j, j, and niches k, k, on the upper portion of the plate, the whole being formed and arranged together so as to present the appearance represented by the annexed photographic drawing.

What we claim as new of our invention or production and desire to secure by Letters Patent, is:-

The ornamental Design for Parlor Stove Plates herein described.
